UNITED STATES PATENT OFFICE

155,294

DESIGN FOR AN ELECTRIC SOLDERING
TOOL

Walter A. Kuehl, Chicago, Ill.

Application November 12, 1948, Serial No. 149,592

Term of patent 14 years

(Cl. D26—1)

To all whom it may concern:

Be it known that I, Walter A. Kuehl, a citizen of the United States, residing at Chicago, in the county of Cook and State of Illinois, have invented a new, original, and ornamental Design for an Electric Soldering Tool, of which the following is a specification, reference being had to the accompanying drawing, forming part thereof, wherein:

Fig. 1 is a perspective view of an electric soldering tool, showing my new design;

Fig. 2 is a front elevational view;

Fig. 3 is a rear elevational view;

Fig. 4 is a top plan view thereof, the tip being broken away for convenience of illustration; and

Fig. 5 is a sectional view along the line 5—5 of Figure 2 looking upwardly and showing the handle portion only, removed from the body of the soldering tool.

I claim:

The ornamental design for an electric soldering tool, as shown.

WALTER A. KUEHL.
